CIRCUIT INTERRUPTER

Leon R. Ludwig, Wilkinsburg, Pa., assignor to
Westinghouse Electric & Manufacturing Com-
pany, East Pittsburgh, Pa., a corporation of
Pennsylvania

Application July 1, 1938, Serial No. 216,884

19 Claims. (Cl. 200—147)

This invention relates to circuit interrupters, and more particularly to arc extinguishers for circuit interrupters of the air break type.

It is an object of my invention to provide an air break circuit interrupter which not only interrupts the circuit, but also restricts and deionizes the arc gases so as to prevent the issuance of flame from the interrupting structure, thereby rendering the interrupter suitable for close mounting in metal cubicles or other enclosed structure.

A further object of my invention is to increase the interrupting capacity of circuit interrupters of the aforesaid type.

Another object of my invention resides in the provision of an arc-extinguishing device for air circuit breakers of high interrupting capacity, which device is equally effective on alternating and direct-current circuits.

A more specific object of my invention is the provision of an arc-extinguishing device for an air circuit breaker of the aforesaid type in which improved arc extinction is obtained by the use of spaced slotted plates of insulating material, and in which arc movement within the slots is obtained by a self-contained magnetic field device thereby eliminating the necessity of a blow-out coil or coils to secure arc movement.

Other objects and advantages relate to details of the interrupting structure such as the thickness of the interrupting plates, the spacing therebetween, the shape of the arc receiving slots and the like, all of which will appear more fully in the following description when taken in connection with the accompanying drawings, in which:

Figure 1 shows the circuit interrupter of my invention in side elevation, a portion of the arc-extinguishing structure being broken away to reveal the position of the arc drawing contacts with respect to the arc-extinguishing device;

Fig. 2 is an enlarged side elevation view partially in section of the arc-extinguishing device of my invention;

Fig. 3 is a front elevation view partially in section of the arc-extinguishing device shown in Fig. 2;

Fig. 4 is a bottom view of the arc-extinguishing device shown in Fig. 2;

Fig. 5 is an exploded perspective view of a group of plates forming part of the arc-extinguishing device shown in the previous figures;

Fig. 6 is an end elevation view of a modified form of plate structure which may be used in the arc-extinguishing device of my invention;

Fig. 7 is a fragmentary sectional view of the

plate structure shown in Fig. 6, taken along the line VII—VII thereof;

Fig. 8 is a fragmentary sectional view showing a plate structure for an arc-extinguishing device similar to that shown in Fig. 7 except that the plates of magnetic material have been omitted;

Fig. 9 is a plan view showing a further form of plate structure capable of use in the arc-extinguisher of my invention;

Fig. 10 is a sectional view of the plate structure shown in Fig. 9 taken along the line X—X thereof;

Fig. 11 is a sectional view of the plate structure shown in Fig. 10, taken along the line XI—XI thereof;

Fig. 12 is an elevation view showing still another arrangement of plate structure capable of use in the arc-extinguisher of my invention; and

Fig. 13 is a sectional view of the plate structure shown in Fig. 12, taken along the line XIII—XIII thereof.

In order to accomplish arc extinction without the issuance of flame exteriorly of the arc-extinguishing structure, numerous devices have heretofore been proposed. One form of arc-extinguishing structure which has proven to be successful commercially comprises a plurality of spaced metallic plates having aligned arc receiving slots therein. The arc to be extinguished is drawn within or at the entrance portion of the slots and is moved to the closed end of the slots, and finally into the metallic plates where it is caused to play as a series of short arcs between the plates. The metal plates in this instance quickly deionize the arc stream and bring about arc extinction without the issuance of flame from the vent passages between the plates. Although this type of circuit interrupter has proven to be effective in interrupting circuits carrying as high as 32,000 amperes at 15,000 volts, great difficulty is encountered in causing currents of substantially greater magnitude to properly transfer to the metallic deionizing plates.

I have discovered that an arc-extinguishing structure employing a plurality of spaced plates of insulating non-gas forming material having aligned arc-receiving slots therein is far more effective than the known arc-extinguishing structure employing metallic plates, and is capable of materially extending the upper limit of current capable of being interrupted. One embodiment of the interrupter which will be hereinafter described in detail, is capable of producing complete circuit interruption of 125,000 amperes at 600 volts alternating current with only $\frac{1}{2}$ cycle

of arcing. When connected to a direct-current circuit the interrupter is capable of interrupting up to 80,000 amperes or more at 750 volts.

The improved interrupting power of my arc-extinguishing structure is based upon the magnetic blast theory and is explained as follows. If an arc is moved laterally in air by a suitable magnetic field against a non-gas-producing solid of such shape that no turbulent flow of gas is produced, the section of the arc remains substantially unchanged and only a slight increase in pressure of the arc gas results. The arc voltage is increased somewhat due to the loss of ions and heat to the restricting walls of the solid. Now if slots or vent openings are placed along the restricting wall so that the pressure is relieved, a strong blast of gas passes through the openings. The arc must, therefore, ionize fresh gas in considerable quantities in order to maintain itself and the arc voltage is thereby greatly increased.

In other words, the effect of the magnetic field is to move ions out of the arc stream. The force exerted by the magnetic field on the ions is transmitted to the gas surrounding the arc in collisions between the ions and the neutral gas molecules. Thus, the moving ions cause un-ionized gas to be placed in motion so that a new supply of cool un-ionized gas is constantly being drawn past the arc. Of course, the ions which are moved into the venting slots will cause the arc to loop or bow somewhat into the slots since the arc attempts to follow the movement of the ions. However, the increasing flow of un-ionized gas into the arc increases the rate of deionization so that in case of alternating current, the arc path quickly becomes non-conducting following a current zero. The rapidly escaping ions through the venting slots as well as the blast of un-ionized gas caused by the magnetic field, produces a rapid rise in arc voltage so as to make the method of arc extinction equally effective on direct current. Arc extinction with the circuit interrupter of my invention is, therefore, accomplished in a manner different from that employed in liquid immersed breakers which subject the arc to a combined blast of arc extinguishing liquid and the products of decomposition of the arc. There is also a marked difference in the manner of arc extinction with my structure and that employed in air or gas blast breakers as heretofore used. Gas blast and air breakers of the prior art depend upon rapid lengthening of the arc by either magnetic or gas blast blow-out means for extinguishing the arc. In my invention, there is substantially no lengthening of the arc as initially drawn, nor is the arc split into a plurality of short serially related sections, as in metallic plate deionizing structures. The specific structure of one device with which I have accomplished my improved results will now be described.

In Fig. 1 of the drawings, the reference numeral 15 designates a panel upon which the interrupter of my invention is mounted. The panel 15 supports a frame 17 which carries a suitable operating mechanism generally indicated at 19. The operating mechanism 19 is not specifically claimed herein and may be of any suitable arrangement, as for instance, that shown in Patent No. 2,177,014, issued October 24, 1939, to W. M. Austin, and assigned to the assignee of the instant application.

The operating mechanism 19 is adapted to actuate a pivoted contact carrying arm 21 hinged to a cross pin 23 to the frame 17. The contact

arm 21 supports a main bridging contact 25, the ends of which are adapted to normally engage the main line contacts 27 and 29. Connected to the main contact 27 is an arcing contact 31 adapted to cooperate with a moving arcing contact 33 carried by a suitable arm 35 supported by the pivoted arm 21. Inasmuch as the specific contact arrangement is not specifically claimed in the instant application, further details of the contact structure may be had by referring to Patent No. 2,214,471, issued September 10, 1940, to L. R. Ludwig and M. E. Horne, and also assigned to the assignee of the instant application.

An arc established by the separation of the arcing contacts 31 and 33 is extinguished by an arc-extinguishing device 37 disposed in partially surrounding relation with respect to the arcing contacts. The arc-extinguishing device 37 is more specifically illustrated in Figs. 2 to 5 inclusive, and comprises a back support plate 39 of insulating material and a front support plate 41 also of insulating material, between which are disposed a plurality of plates of insulating material spaced from each other by plates of magnetic material. The general shape and arrangement of these plates are more clearly shown in Fig. 5, which represents a group of plates disposed within the space indicated by the bracket at X in Fig. 2.

As shown in Fig. 5, the lowermost plate 43 is constructed of insulating material and preferably of refractory or other material that is substantially free from substance which gives off gas when acted upon by an arc such for example as asbestos board, quartz, soap stone or titanium oxide. Cold molded compositions as for instance a product known as artificial porcelain comprising 30% talc, 2% feldspar and 68% clay may also be used. In general all materials which are refractory in nature and have the requisite mechanical strength are suitable for this purpose. The preference for non-gas forming materials will be made known hereinafter. The plate 43 is provided with a notch or slot 45 extending from the lower end thereof inwardly and tapers from a relatively wide width at the edge of the plate to a narrow slot-like portion at the closed end thereof. The outline of the slot 45 is perhaps more clearly shown in Fig. 3. Adjacent the plate 43 disposed on either side of the slot 45, is a pair of plates 47 of magnetic material, such as iron or steel, which serve as spacers between the insulating plate 43 and the next adjacent insulating plate 49. The iron plates 47 also serve to produce a magnetic field to facilitate arc movement upwardly in the slot 45, as will be explained more fully hereinafter.

The plate 49 is similar in construction to plate 43, with the exception that it is somewhat shorter and is adapted to support a transversely extending plate 51 of magnetic material across the upper end thereof, the purpose of which will also appear hereinafter. Two sets of plates 47 are also disposed between the plate 49 and a plate 53, the latter plate being similar to plate 43, with the exception that the entrance portion of its slot 45 has been extended and is of a smooth contour, whereas the entrance portion of the slot 45 in plate 43 is provided with two arcuate cutout portions, as shown at 55, for the purpose of accommodating the fixed arcing contact structure 31.

With particular reference to Fig. 2 the insulating plates to the right of the portion indicated at X have identically the same slot contour as that

shown by the plate 53 in Fig. 5. The insulating plates to the left of the portion indicated at X have the same slot contour as plate 43.

Each of the plates 43, 49 and 53 of insulating material, as well as the plates 41 of magnetic material, are provided with apertures 57 as shown in Figures 3 and 5. These apertures permit the assembly of the respective plates in the order shown upon four tubular members 59 of insulating material. The stack of plates is firmly held together by bolts 61 passing through the two lowermost tubular members 59 and the respective front and back supports 39 and 41. Either side of the plate assembly is provided with a cover plate 63 secured to the respective front and back supports by screws 65, as shown. The plates 51 of magnetic material disposed in abutting relation with respect to the plates 49, are prevented from movement away from the plates 49 by means of bar members 67 secured to each of the side plates 63, and which register with the rectangular detents 69 provided in the plates 51.

The front support 41 is also provided with a cover plate 71. The complete arc-extinguishing assembly 37 is secured to the breaker panel 15 by means of bolts 73 extending through the upper tubular members 59 of insulating material and which are anchored to suitable fastening means not shown, provided in the panel. The arc-extinguishing device 37 is positioned with respect to the fixed arcing contact 31 by means of a semi-circular support 75 which forms part of the fixed arcing contact assembly and upon which the back support plate 39 is adapted to rest. In order to properly center the arc-extinguishing device 37, the back support plate 39 is provided with a semi-circular notch or detent 77 as more clearly shown in Figs. 2 and 3. The support member 75 is adapted to register with the notch 77 when the arc-extinguishing structure 37 is in place. When thus positioned and with movement of the arcing contact 33 to the open position, the path of movement of the contact 33 takes place centrally within the aligned slots 45 of the respective plates of insulating material.

When an arc is established by the separation of contacts 31 and 33, the plates 41 of magnetic material cause the arc to be moved upwardly in the slots 45 towards the closed end thereof. The magnetic reaction is increased by the transversely extending plates 51 disposed in abutting relation with the plates of insulating material 49. It will also be observed that the transverse plates 51 of magnetic material are of the same thickness as the plates 49 of insulating material, so that the plates 41 of magnetic material provide a venting space or channel between adjacent plates of insulating material that is free and unobstructed.

Thus as the arc is drawn between the arcing contacts 31 and 33, and moves to the closed end of the slots 45 in accordance with the foregoing theory, it will be subjected to a strong blast of gas set up by the magnetic field moving the arc upwardly. The use of gas-forming insulating material for the plates 43, 49 and 53 is undesirable in that the action of the arc upon such material produces gas in such quantities so as to act explosively upon the arc which tends to blow the arc out of the slots 45 and in general hinders arc movement towards the closed ends of the slots. The arc is prevented from being moved or looped a substantial distance between the plates of insulating material by the proper selection of thickness of the insulating plates, and also the spacing between the plates of insulating material, as

well as the cross-sectional area of the venting passage between the plates. In practice, I have found that the plates of insulating material may vary from $\frac{1}{8}$ " to $\frac{1}{4}$ " and the spacing between plates of insulating material may vary from $\frac{1}{8}$ " to $\frac{1}{4}$ ". The plates of magnetic material 41 preferably have such a width that the space therebetween at the most constricted portion is from $\frac{1}{8}$ square inch to $\frac{3}{4}$ square inch. I have found that if the cross-sectional area of the venting passages is too great, there is a marked tendency for the arc to elongate and be driven through the venting passages and out the open end thereof.

I have also discovered that the shape of the slot 45 is of importance in obtaining free and unimpeded movement of the arc, particularly of the higher current values upwardly towards the closed ends of the slots. For example, I have found that a slot that varies in width from $\frac{1}{8}$ " at its apex to $\frac{1}{8}$ " at a point two inches removed therefrom, has substantially the proper taper at its upper or extremely narrow end. The lower portion of the slot, however, may increase in width more rapidly and so long as the sides thereof have a smooth contour and are of sufficient width to permit the moving arcing contact 33 to pass therethrough, no difficulty is experienced in obtaining the requisite arc movement. In general, the shape of the slot 45 may be such that

$$\frac{dw}{dl}$$

increases as l increases, where l is the distance measured along the axis of the slot from its apex and w is the width of the slot measured perpendicular to the axis. The taper or the rate at which the slot changes its width may also be expressed as halving in width in every longitudinal distance of from $\frac{1}{8}$ " to 2 inches.

In order to prevent gases resulting from an arc within the slots 45 at the time of contact separation or shortly thereafter from being directed downwardly and against the circuit interrupter contact mechanism, I have provided two opposed deflecting members 79 disposed on either side of the path of movement of the contact 33, and respectively secured to the side cover members 63. The deflecting members 79 provide a throat or orifice-like passage in which moving contact 33 operates, and further provides a pocket immediately above the members, in which the gases are entrapped, deflected and caused to be directed upwardly in the event that the current being interrupted is sufficiently great to cause a blast of gas having a tendency for downward movement. This tendency for downward movement, however, persists only for a short interval of time and gives way to the effect of the magnetic field which drives the arc gases as well as considerable quantities of un-ionized gas upwardly of the slots and through the spaces between the plates of insulating material.

I have also discovered that effective arc extinction may be attained by modifying the plate arrangement within the arc-extinguisher 37 as shown in Figs. 6 and 7. As shown in these two figures, a plate 81 of insulating material, having a slot 83 therein, is placed on either side of a plate 85 of magnetic material having a slot 87 therein of substantially larger dimensions than the slot 83. The combination of two plates 81 of insulating material and a single plate 85 of magnetic material may be arranged as shown

in Fig. 7 and assembled with spacing members 89 disposed therebetween so as to provide vent passages adjacent the arc and through which a blast of gas may be directed to aid in extinguishing the arc.

Although the plates of magnetic material produce superior performance, I have also discovered that a successful arc-extinguishing structure may be produced by the use of spaced plates of insulating material without plates of magnetic material or other magnetic means disposed therebetween, as shown in Fig. 8. In Fig. 8 the plates 81 correspond in shape to the plates 81 of Fig. 6, and are provided with spacers 89 without the use of magnetic material. The absence of iron or other suitable magnetic material in the arc-extinguishing device as schematically illustrated in Fig. 8, permits a more rapid rise of arc voltage but also has the tendency of permitting the arc to be blown through the venting spaces between the plates of insulating material and appear exteriorly of the arc-extinguishing device before the arc is extinguished. The addition of iron or other magnetic material to the arc-extinguishing structure has a marked inductive effect and greatly reduces the transient voltage rise preceding current interruption, and also limits the amount of movement of the arc into the venting spaces between the plates of insulating material, thereby lessening the danger of flame from appearing exteriorly of the arc-extinguishing device. Therefore, a further advantage in the use of magnetic material in the arc-extinguishing structure resides in the provision of means for moving the arc quickly towards the apex of the slots in the plates of insulating material without movement of the arc beyond the ends of the plates.

In Figs. 9 to 11, a modified plate structure is illustrated in which plates of insulating material 91 are spaced from each other by narrow plates 93 of magnetic material disposed on either side of the arc-receiving slot 95. The magnetic effect of the plates 93 of magnetic material is strengthened by the addition of a yoke 97, also of magnetic material, disposed about the upper end of the plate assembly. The arc-extinguishing operation, however, is performed in a manner as heretofore described.

Figs. 12 and 13 illustrate a further possibility of plate structure which constitutes alternate plates 101 of insulating material having a slot 103 therein and plates 105 of magnetic material of inverted U-shape, as shown in Fig. 12. Thus the plates 105 provide a spacing between the plates 101 of insulating material and also provide a strong magnetic field for moving the arc towards the closed end of the slot 103. The plates 105 in this instance are of considerably greater length than the plates 101 so as to provide a suitable venting passage 107 between the adjacent plates of insulating material.

Although I have shown and described a specific circuit interrupter and a number of arc-extinguishing devices therefor, it is to be understood that the same is for the purpose of illustration and that changes and modifications may be made by those skilled in the art without departing from the spirit and scope of the appended claims.

I claim as my invention:

1. In a circuit interrupter, means for establishing an arc, an arc-extinguishing structure for extinguishing said arc comprising means of insulating material having a V-shaped slot therein in which said arc is adapted to play, said slot

decreasing progressively in width from one side thereof to the other and terminating in a constricted closed end tip, said constricted tip decreasing in width from no greater than one-eighth inch at a point at least two inches from its apex to no greater than one-sixteenth inch at its apex, said means of insulating material having venting passages therethrough communicating at spaced intervals with at least the constricted tip of said slot, means for moving said arc into said constricted tip where it is adapted to play until extinguished, and means for subjecting said arc to a blast of un-ionized gas while playing in said constricted tip.

2. In a circuit interrupter of the air blast type, an arc extinguishing device comprising means of non-gas-forming insulating material having a tapered notch extending inwardly from one end thereof and a plurality of spaced venting passages leading from said tapered notch, means for establishing an arc within the larger portion of said notch, said tapered notch terminating in a constricted tip which progressively decreases in width to the closed end thereof and which has a width at its entrance portion to preclude alternating current arcs above a predetermined instantaneous current magnitude from entering therein, and means for moving said arc laterally within said notch and into said constricted tip following decay of the instantaneous current below said predetermined magnitude, said means causing a blast of un-ionized gas through the arc stream and the venting passages in said means of insulating material to assist in extinguishing the arc.

3. In a circuit interrupter, means for establishing an arc, an arc-extinguishing structure for extinguishing said arc comprising a plurality of plates of insulating material having through venting spaces therebetween and slots of V-shape in which said arc is adapted to play, said slots decreasing progressively in width from one side thereof to the other and terminating in the constricted closed end tip, said constricted tip decreasing in width from no greater than one-eighth inch at a point at least two inches from its apex to no greater than one-sixteenth inch at its apex, means for moving said arc into said constricted tips where it is adapted to play until extinguished, and means for subjecting said arc to a blast of un-ionized gas while playing in said constricted tip.

4. In a circuit interrupter, an arc-extinguishing device, comprising a plurality of spaced plates of non-gas-forming insulating material, said plates having substantially aligned tapered slots extending inwardly from one of their ends, means for establishing an arc within the larger portion of said slots, said slots terminating in constricted tips which progressively decrease in width to the closed ends thereof and have a width at their entrance portion to preclude alternating current arcs above a predetermined instantaneous current magnitude from entering therein, and magnetic means for moving said arc laterally within said slots and into said constricted tips following decay of the instantaneous current below said predetermined magnitude, said magnetic means causing a blast of un-ionized gas through the arc stream and the spaces between the plates of insulating material to assist in extinguishing the arc.

5. In a circuit interrupter, an arc-extinguishing device comprising a stack of plates of insulating material, means spacing said plates a pre-

venting passages, said plates being substantially determined distance from each other to provide free from materials which give off gas when acted upon by an arc and having elongated tapered notches therein, said tapered notches decreasing progressively in width from the open to the closed ends thereof and having a constricted portion of at least two inches in length adjacent the closed ends thereof of width to prevent entry thereinto of alternating current arcs of a predetermined instantaneous current magnitude, means for establishing an arc within said notches, and means for moving the arc into the constricted portion of said notches following decay of the instantaneous value of the arc current below a predetermined magnitude where it is cooled and extinguished.

6. In a circuit interrupter, an arc-extinguishing device comprising a stack of plates of insulating material, means spacing said plates a predetermined distance from each other to provide vent passages therebetween, said plates being substantially free from materials which give off gas when acted upon by an arc and having aligned elongated tapered notches therein, means for establishing an arc within said aligned notches, and plate means of magnetic material disposed within said stack adjacent the closed ends of said aligned notches to provide an intense magnetic field for moving the arc against the closed end of said aligned notches where it plays until extinguished, said plate means of magnetic material being placed in abutting relation with and across the outer edges of a plurality of plates of insulating material so as not to restrict the venting passages between said plates of insulating material.

7. In a circuit interrupter, an arc-extinguishing device comprising a stack of plates of insulating material, means spacing said plates a predetermined distance from each other to provide vent passages through the stack, said plates being of refractory material and having elongated tapered notches therein which terminate in a constricted tip decreasing progressively in width from no greater than one-eighth inch at a point at least two inches from the closed end of the notches to no greater than one-sixteenth inch at the closed end, means for establishing an arc within said aligned notches, and plates of magnetic material disposed at spaced intervals in the stack of plates of insulating material to provide an intense magnetic field for moving the arc into the constricted tips of said notches where it plays until extinguished.

8. In a circuit interrupter, an arc-extinguishing device comprising means of insulating material substantially free from material which gives off gas when acted upon by an arc, said means of insulating material defining an elongated V-shaped notch and a plurality of spaced venting passages therethrough communicating at least with the closed end of said notch, means for establishing an arc within said notch, and means of magnetic material embedded in said means of insulating material but disposed outside said venting passages for producing a magnetic field to move the arc toward the closed end of said notch where it is adapted to play without substantial looping into said venting passages.

9. In a circuit interrupter, an arc-extinguishing device comprising a stack of plates of insulating material, said plates being substantially free from materials which give off more than a small quantity of gas when acted upon by an arc and

having elongated tapered notches extending inwardly from one end thereof, means spacing said plates from each other to provide venting passages therebetween in alignment with the longitudinal axes of said notches, means for establishing an arc within said notches, and plate means of magnetic material disposed at intervals in the stack but disposed outside said venting passages for producing a magnetic field to move the arc toward the closed end of said notches and a blast of gas through the arc to aid in extinguishing the arc, said plates of insulating material being spaced from each other a distance to prevent substantial movement of the arc therebetween.

10. In a circuit interrupter, an arc-extinguishing device comprising a stack of plates of insulating material, said plates of insulating material being substantially free from materials which give off gas when acted upon by an arc and having slots of V-shape therein, plates of magnetic material disposed between said plates of insulating material on either side of said slots and extending longitudinally of said plates of insulating material to provide vent passages of predetermined cross-sectional area in alignment with said slots, means for drawing an arc within said slots, said plates of magnetic material providing a magnetic field for moving the arc toward the closed ends of said slots, and additional plates of magnetic material disposed transversely of said longitudinally disposed plates of magnetic material for strengthening the magnetic reaction for moving said arc, said plates of insulating material being spaced from each other a distance to prevent substantial movement of the arc therebetween.

11. In a circuit interrupter, an arc-extinguishing device comprising a stack of plates of insulating material, said plates of insulating material being substantially free from materials which give off gas when acted upon by an arc and having aligned slots of V-shape therein, plates of magnetic material disposed between said plates of insulating material on either side of said aligned slots and extending longitudinally of said plates of insulating material to provide vent passages of predetermined cross-sectional area in alignment with said slots, means for drawing an arc within said aligned slots, said plates of magnetic material providing a magnetic field for moving the arc against the closed ends of said aligned slots where it is adapted to play until extinguished, and additional plates of magnetic material disposed transversely of said longitudinally disposed plates of magnetic material for strengthening the magnetic reaction for moving said arc, said additional plates of magnetic material being disposed in abutting relation to said plates of insulating material and having substantially the same thickness so as to prevent obstructing the vent passages between said plates of insulating material.

12. In a circuit interrupter, an arc-extinguishing device comprising a stack of plates of insulating material having elongated tapered notches extending inwardly from one end thereof, means for drawing an arc within said notches, plates of magnetic material disposed longitudinally of said plates of insulating material on either side of said notches to maintain said plates of insulating material spaced apart from each other and to move the arc toward the closed end of said notches, and a yoke of magnetic material surrounding the end of said plates of insulating and

of magnetic material opposite said notches to strengthen the magnetic field set up by the arc within said plates of magnetic material.

13. In a circuit interrupter of the air break type, arc extinguishing means comprising a plurality of plates of insulating material, said plates being substantially free of material which gives off a gas when acted upon by an arc and having elongated tapered slots extending therein from one edge thereof, means for establishing an arc within said slots, said slots having a constricted portion which decreases progressively in width to the closed end thereof and is so narrow that alternating current arcs of relatively high instantaneous current magnitude will not enter 15 therein but will permit entry only of arcs of less than a predetermined instantaneous current magnitude, and magnetic means for moving the arc laterally toward the closed ends of said slots, said arc playing outside said constricted portion until the instantaneous current has been reduced to said predetermined value whereupon it is moved by said magnetic means into said constricted portion where it is quickly cooled and extinguished.

14. In a circuit interrupter, arc-extinguishing means of insulating material comprising a plurality of plate portions, spaced from one-eighth inch to one-fourth inch apart, said plate portions being free from large quantities of materials which give off a gas when acted upon by an arc and having a thickness from one-eighth inch to one-fourth inch, said plate portions having slots extending therein from one edge thereof, means for establishing an arc within said slots, and members of magnetic material to assist movement of the arc against the closed end of said slots, the magnetic field produced by said magnetic members also causing a blast of cool un-ionized gas to be moved through the arc as it plays against the closed end of said slots.

15. In a circuit interrupter, arc-extinguishing means comprising a plurality of plates of insulating material, spaced from one-eighth inch to one-fourth inch apart, said plates being substantially free from materials which give off a gas when acted upon by an arc and having a thickness from one-eighth inch to one-fourth inch, said plates having aligned slots extending therein from one edge thereof, means for establishing an arc within said slots, and members of magnetic material disposed between said plates of insulating material longitudinally thereof on either side of said slots to assist movement of the arc against the closed end of said slots, said members of magnetic material serving to space said plates of insulating material apart and being displaced laterally from each other so as to provide a venting space between adjacent plates of insulating material having a cross-sectional area of from one-eighth square inch to three-fourths square inch, the thickness of said plates of insulating material, the spacing between said plates and the cross-sectional area of said venting spaces cooperating to prevent substantial 65

lengthening of the arc and movement thereof between said plates of insulating material.

16. In a circuit interrupter, arc-extinguishing means comprising a plurality of spaced plates of insulating material, said plates of insulating material being of substantially refractory material and having elongated tapered notches therein aligned at least at the open ends thereof, a pair of contacts at least one of which is adapted to be moved within said aligned notches to establish an arc therein, and means disposed on either side of the path of movement of said movable contact adjacent the open ends of said aligned notches and arranged to close the open ends of said notches except for the space required for contact movement to cause the gas produced by said arc upon separation of said contacts to expand laterally and in a direction away from said contacts so as to prevent said gas from being blown out of the open end of said notches.

17. In a circuit interrupter, arc extinguishing means comprising means of insulating material having an elongated V-shaped groove extending inwardly from one end thereof, said means of insulating material having spaced venting passages therethrough communicating with said groove, contact means separable within the open end of said groove for establishing an arc, and lining members disposed laterally of said contact means and arranged to close in part the open end of said groove to prevent arc gases from being blown out of said groove in the direction of said contact means.

18. In a circuit interrupter, arc extinguishing means comprising a plurality of plates of insulating material, each of said plates having an elongated V-shaped slot extending inwardly from one end thereof, means spacing said plates from each other to provide venting passages therebetween, contact means separable within the open ends of said slots for establishing an arc, and deflecting members of insulating material disposed laterally of said contact means adjacent the ends of said plates to substantially close the spaces between said plates on each side of said slots, said deflecting members extending inwardly with respect to the open ends of said slots to provide a constricted entrance passage to said slots for preventing arc gases from being blown out of said slots in the direction of said contact means.

19. In a circuit interrupter, arc extinguishing means comprising a plurality of plates of insulating material having elongated V-shaped slots extending inwardly from one end thereof, means for establishing an arc within said slots, and plates of U-shaped magnetic material disposed between said plates of insulating material having the legs of the U on opposite sides of said slots for moving said arc towards the closed ends of said slots, the transverse portion of said plates of magnetic material extending beyond the plates of insulating material to provide venting passages between said transverse portions and said plates of insulating material.

LEON R. LUDWIG.
